UNITED STATES PATENT OFFICE.

CALVERT B. COTTRELL, OF WESTERLY, RHODE ISLAND.

OFFSET MECHANISM FOR PRINTING-MACHINES.

SPECIFICATION forming part of Letters Patent No. 425,123, dated April 8, 1890.

Application filed October 11, 1889. Serial No. 326,655. (No model.)

To all whom it may concern:

Be it known that I, CALVERT B. COTTRELL, of Westerly, in the county of Washington and State of Rhode Island, have invented a new and useful Improvement in Offset Mechanism for Printing-Machines, of which the following is a specification, reference being had to the accompanying drawings.

This invention is more especially applicable to that class of printing-machines known as "perfecting-machines."

The improvement relates to an automatically-shifting tympan employed on an impression-cylinder, and more especially on the second impression-cylinder of a perfecting-machine, the object being, generally, the prevention or reduction of the tendency to what is known as "set-off," or transfer of ink from the tympan onto the printed sheet while the latter is receiving its second impression.

In my Letters Patent of the United States Nos. 175,036 and 175,037, both dated March 21, 1876, there are described and claimed automatically-shifting tympans. According to the descriptions contained in the specifications of both of those patents, the tympans are shifted a short distance during every revolution of the impression-cylinder to which they are applied; but according to the present invention the desired effect is much better accomplished by allowing the tympan to remain stationary relatively to its cylinder during several revolutions of the cylinder, and then shifting it at once the whole distance necessary to present an entirely fresh and clean portion of the tympan on the exterior of the cylinder.

I will now proceed to describe my invention with reference to the accompanying drawings and afterward point out its novelty in the claims.

Figure 1 of the drawings represents a longitudinal vertical section of an impression-cylinder and parts of the framing of a printing-machine and of the devices and appurtenances belonging thereto involved in my invention. Fig. 2 represents an end view of the cylinder and a vertical section of those parts which are attached to the framing, taken in the line xx of Fig. 1, as viewed from the right side of that figure. Fig. 3 represents a transverse vertical section of the cyl-

inder and its appurtenances, taken in the line yy of Fig. 1, looking from the right of that figure, and also showing in dotted outline certain parts, the position of which is outside of said line yy . Fig. 4 is a perspective view of a portion of the gearing through which the shifting of the tympan is effected by the rotary motion of the cylinder. Fig. 5 is a view corresponding with part of Fig. 1, but on a larger scale. Figs. 6 and 7 are diagrams representing the principal parts of two different kinds of perfecting-presses, and illustrating the application of my invention to each. Fig. 8 represents the same end of the cylinder as is shown in Fig. 2, and illustrates a modification of a portion of the tympan-shifting mechanism. Fig. 9 is a sectional view at right angles to Fig. 8 of some of the details of that figure.

Similar letters and numerals of reference designate corresponding parts in all the figures.

A, Figs. 1, 2, 3, and 8, designates the impression-cylinder—forexample, the second impression-cylinder of any perfecting-machine—the shaft A' of said cylinder having its bearings in boxes A^2 , supported in the stationary side frames B , Fig. 1, of the machine. This cylinder is represented as having tympans c in four sections, each of which will be hereinafter referred to as a "shifting tympan," each covering a portion of the circumference of the cylinder included between two longitudinal openings e , the number of said openings corresponding with the number of tympans c . Each of these tympans c consists of a roll of paper nearly as wide as the cylinder and of a length many times what is required to cover one of the divisions of the cylinder between two openings e . One end of the roll is fastened to a roller d , and the other end to a roller j , there being two such rollers for every tympan, the said rollers, which may be termed the "tympan-rollers," being within the cylinder, and their journals having bearings $d' j'$ provided for them in the heads of the cylinder, and the roll of paper being capable of being unrolled from one roll and rolled onto the other. Between the said rollers $d j$ each tympan runs from the roller d over a rod a , supported in the cylinder-heads; thence through one opening e of the cylinder over

the circumference of the cylinder to the next of said openings *e*, over a rod or roller *g*, arranged in said opening; thence over and between the feed-rollers *h i*, which have their 5 bearings *h' i'* in the cylinder-heads, and thence to the roller *j*. The tympan-roller *j*, which may be called the "take-up" roller, as the web is taken up by it from the roller *d* for the shifting of the tympan-surface outside of 10 the cylinder, is geared at each end with the feed-roller *h* by friction wheels or gears *k l*, and the said roller *j* is furnished inside of the cylinder with a ratchet-wheel *j'*, which is engaged by a spring-actuated pawl *j''*, attached 15 to one of the cylinder-heads for the purpose of retaining the portion of the tympan *c* wound upon said roller. On one end of the tympan-roller *d*, which may be termed the "delivery-roller," there is within the cylinder 20 a ratchet-wheel *d'*, which at all times except during the unwinding of the roll from the said roller is engaged by a pawl *d''*, which forms part of a small lever working on a fulcrum-pin *d'*, secured in one of the cylinder-heads. 25 The ends of the roll of paper may be fastened to the rollers *d* and *j* by hooks, clamps, or other suitable means.

One end of the shaft of each feed-roller *h* of the tympan projects outward some distance beyond the corresponding end of the cylinder, as shown in Fig. 1, and also in Fig. 5, and the so projecting part has loosely fitted to it a spur-gear *s*, the elongated hub *s'* of which (see Fig. 5) is fitted to turn freely in a 30 sleeve *o*, on the exterior of which is a screw-thread of rapid pitch, which is fitted to a corresponding female screw-thread in a bushing *p*, which is secured by screws *p'* into an annular plate *A'*, which is secured to the cylinder concentric therewith by stud-bolts *a'*. The spur-gear *s* has firmly secured to it one 35 half of a ratchet-clutch *t*, the other half of which is secured to the shaft of the roller *h*. Firmly secured upon the outer end of the 40 screw-threaded sleeve *o* is a lever *n*, having two arms of equal length and having on one arm an anti-friction roller *m* and on the other arm an anti-friction roller *m'*.

C designates a spur-gear (shown dotted in 45 Fig. 2 and in section in Fig. 1) concentric with the cylinder, but stationary at that end of the cylinder on which the gears *s* are situated. This gear consists of a ring held by brackets *C'*, which are secured to any convenient portion 50 of one of the side frames *B*—as, for instance, the cylinder-box. The several gears *s* belonging to the several tympans are always in gear with this stationary gear *C* in readiness to drive the tympan-rollers *h* for shifting 55 the tympans by the revolution of said gears around the stationary gear *C*; but the shifting of the tympans is only effected while the clutch *t* is in gear, the said gears running loose upon the shafts of their rollers at all 60 other times.

D and *E* are two spur-gears concentric with the cylinder, arranged close together on the

same side thereof as the spur-gear *C*. The outer spur-gear *D* consists simply of a toothed ring, which is held stationary by being secured to parts of the same brackets *C'* which support the gear *C*. The gear *E* is fitted to turn loosely on the adjacent cylinder-head, and its own hub *E'* projects through the outer gear or toothed ring *D*, as shown in Figs. 2 70 and 4.

The gears *D* and *E* are approximately of the same pitch, but the gear *D* has one more tooth than the gear *E*. In the example represented the gear *D* is supposed to have eighty 80 teeth and the gear *E* to have seventy-nine. Both of these gears gear with a spur-gear *F*, (see Figs. 2 and 4,) which turns loosely on a stud *F'*, secured in the cylinder-head.

U designates a bent lever, which hangs on a fixed fulcrum consisting of a stud-bolt *v*, (see Figs. 1 and 2,) secured in a convenient part of the side frame *B* on the same side of the machine as that on which the levers *n* are situated. This lever is shown fully in Fig. 2 85 and in section in Fig. 1. It has upon one arm an offset *u*, (see Fig. 2,) which constitutes a movable cam-surface for acting, as herein-after described, on the rollers *m* on the inner ends of the levers *n*, and the extremity *u'* of 90 the said arm is capable of engagement with either of two hooks 20 21 on the lower arm of an elbow-lever *W*, hereinafter termed the "trip-lever," which works on a fulcrum consisting of a stud-bolt 19, secured in the side 95 frame, and the other arm of which is furnished with an anti-friction roller 10, to be operated upon by a stud 9, which projects from the hub *E'* of the spur-gear *E*. The outer end of the lever *U* is furnished with an anti-friction 100 roller *u'*, to be operated upon by a cam *H*, (see Fig. 2,) secured to the adjacent end of the cylinder. The cam-lever *U* has applied to it a pushing-spring *w*, which takes its bearing against one of the brackets *C'*, for the 105 purpose of pushing it outward as far as permitted by the hook 20 or 21 of the elbow-lever *W*, which may be at any time engaged with the extremity *u'* of the cam-lever. The trip-lever *W* is connected with one of the 110 brackets *C'* by a pulling-spring *Y*, to keep it in engagement with the extremity of the cam-lever *U*, as shown in Fig. 2. On the same 115 side of the machine as the levers *U* and *W*, but on the opposite side of the axis of the cylinder, there is secured to the side frame a stationary cam *N*, for acting, as herein-after described, on the rollers *m'* at the outer ends of the levers *n*. The purpose of the cam-lever *U*, the levers *n*, the screw-threaded sleeve *o*, the trip-lever *W*, the stud 9, the gears *D E F*, and the cam *H* is the 120 throwing of the clutches *t* into gear at the proper time to produce the shifting of the tympans after a certain number of revolutions of the cylinder has been made, and afterward to throw the said clutches out of gear 125 to leave the shafts of the rollers *h* free from the gears *s*, as will be herein-after described.

I have hereinbefore described a ratchet-wheel d^2 on each of the tympan-rollers d , and a pawl d^3 for engaging the same. This pawl d^3 requires to be thrown out of gear from its 5 respective ratchet-wheel prior to the operation of shifting the tympan. For the purpose of throwing this pawl out of gear with its ratchet, it is connected with the outer end of its respective lever n by means which I 10 will now describe with reference to Figs. 2 and 3.

11 is a rod connecting the outer end of the lever n with one arm 12 of a rock-shaft 13, which is supported in the ring A^4 and the adjacent cylinder-head, another arm 14 of the said rock-shaft being connected by a rod 15 with the outer end of the pawl-lever d^3 . For the purpose of keeping this pawl in gear at all times, except when the pawl is intended 20 to be thrown out of gear with its ratchet-wheel, there is coiled round its respective rod 11 a spring 16, one end of which has a bearing against a fixed guide 17, secured to the ring A^4 , the other end of which bears against a 25 collar 18 on the said rod. This spring 16, while strong enough to hold the pawl in gear until it is required to be thrown out, is not strong enough to overcome the friction between the bushing p and the screw-threaded sleeve to 30 which the said lever n is attached.

In order to provide for the insertion of the tympan-rollers d and j into the cylinder and their removal therefrom with the roll of paper which serves as the shifting tympans, the 35 bearings d' and j' for the said rolls are not made directly in the cylinder-heads, but in cap-pieces G , which are fitted to openings G' , provided in the cylinder-heads, the said openings being large enough to permit the insertion 40 of the said rollers and the roll of paper through the cylinder-heads. Each opening G' is represented of a size and form to admit the roller d of one tympan and the roller j to the next tympan. The cap-plates G are of 45 skeleton form, having openings in them large enough to admit the arms of the attendants for the purpose of making ready the tympans for printing.

Before describing the operation of shifting 50 the tympan I will mention that the blanket which is represented under the tympan in dotted lines in Fig. 3 may be attached to one end of the rod a , hereinbefore mentioned as one of the guides for the tympan, and at the 55 other end to a rod b , which is supported in the cylinder-heads.

The operation of shifting the tympan is as follows: The shifting tympan having been 60 put on each section of the cylinder, as described, the extremity u^* of the cam-lever N is brought into the inner hook 20 of the trip-lever W , in which position the movable cam u will be out of the way of the rollers m of the levers n , the said levers being then in 65 such position that the screw-threads on their surface hold the clutches t out of gear, keeping the feed-rollers h out of gear from the

spur-gears s . When the levers are in this position, their rollers m' are in such position that they will not strike the stationary cam N in their rotation with the cylinder. The press being then started, the cylinder revolves in the direction of the arrow 23. (Shown in Figs. 2 and 3.) The gear F revolving with the cylinder in gear with the stationary gear 70 D and the loose gear E causes the latter to turn slowly in the opposite direction to the cylinder at the rate of one tooth for each revolution of the cylinder. After a certain number of revolutions have been made the gear 80 E is turned until the stud 9 on its hub comes in contact with the roller 10 on the trip-lever W and moves the said lever so far that its inner or upper hook 20 slips from under the extremity u^* of the cam-lever U and allows 85 the said cam-lever to be forced outward by the spring into the outer or lower hook 21, as shown in Fig. 2. Then, when the portion of a tympan which is exposed on the surface of the cylinder is clear from the web of printed 90 paper, the roller m on its respective lever n comes in contact with the movable cam u on the lever U , and the said lever n is turned in the direction of the arrow 24. (Shown in the lower part of Fig. 2.) This movement of the 95 lever n , operating through the rod 11 and through the connections hereinbefore described between the said rod 11 and the pawl d^3 , liberates the ratchet-wheel d^2 . At the same time the screw-threaded sleeve o , turning with the lever n , to which it is attached, is caused to be screwed inward in its bushing p , and so to push the gear s and the portion of the ratchet-clutch thereto attached into gear with the other portion of the said clutch 105 on the friction-wheel k . The said gear s is always turned while the cylinder revolves, and when the ratchet-clutch comes into gear the feed-roller h turns with the said gear, and the feed-roller i turns with it by the 110 friction of the tympans between them. The take-up roller j is at the same time turned by the friction between the friction-wheels k and l , and thus the tympan is drawn from the roll on the roller d and wound upon the 115 roller j . The feed-rollers h and i turn sufficiently while the lever n of the roller h moves from under the cam u to a position near the cam N to move the tympan in the direction of the circumference of the cylinder a distance about or nearly equal to the 120 distance between two openings e , or about equal to the length of the form in that direction, and thus to present at one operation an entirely fresh and clean portion of 125 the tympan on the exterior of the cylinder. When the feed-roller h approaches the cam N , the roll m' on its lever n strikes the cam N , and the lever n is thus turned in such direction that the screw-threaded bushing o , to 130 which it is attached, is screwed outward in the bushing p and caused to ungear the clutch t , and the tympan then stops shifting. In the meantime the tympan on another section of

the cylinder included between two openings *e* is shifting. When the several sections of the cylinder have clean tympans and before either feed-roller *h* of the tympans has reached 5 the movable cam *u* a second time, the cam *H* on the cylinder comes in contact with the roll *u'* on the cam-lever *U* and lifts the end *u** of the said lever into the upper or inner hook 10 of the trip-lever *W*, so that the roll *u'* on the lever *n* of the tympan will pass the said movable cam *u* without striking. Then the cylinder makes a number of revolutions until the pin 9 again reaches the roller 10 of the trip-lever *W*, when the cam-lever *U* is 15 again tripped and the shifting operation is repeated. The number of revolutions thus made before the pin 9 again reaches the roller 10 depends upon the number of teeth in the spur-gears *D E*. If it be desired to shift not 20 so often, the gears *D* and *E* should have a larger number of teeth. The frequency of the shifting may, however, be increased by putting one or more additional pins 9 in the hub *E'* of the gear *E*.

25 In some cases it may be desirable to provide for tripping the cam-lever *U* by hand to produce the shifting of the tympan at a desirable time. In such case, instead of arranging the trip-lever *W* loosely on the fixed ful-

30 crum 19, as shown and described with reference to Fig. 2, I fasten said lever upon the inner end of a short arbor 19*, as shown in Figs. 8 and 9, which works in a fixed bearing provided in the cylinder-pocket or suitable portion of the adjacent side frame *B* of the machine, and on the outer end of the said arbor which projects through the outside of the said side frame I affix a small hand-lever *W'*, by which at the proper time the hooked arm of 35 the said lever *W* may be operated to trip the cam-lever in the same way as when automatically tripped by the action of the stud 9, hereinbefore described. In order to prevent the trip-lever from being moved farther than it 40 is necessary to effect the tripping of the cam-lever, a stop *x'* is provided for the hand-lever *W'*. This stop *x'* is represented as consisting of a pin secured in the outside of the side frame.

45 As it is necessary that the tripping should occur at the proper stage of the revolution of the cylinder, as hereinbefore described, some means must be provided by which the tripping at any other time is prevented, and for this purpose I provide upon the outside of 50 the cylinder a flange or annular projection *z*, (see Fig. 8,) which is concentric with the cylinder, and the external circumference of which is slightly within the radius of the outside of 55 the cam *H*. This flange or projection *z* is in a position for the roller *u'* of the cam-lever *U* to be just outside of it when the end of the said lever is engaged by the hook 20 on 60 the trip-lever. The said flange or projection *z* is not a complete circle, but terminates on each side of the cam *H*, so as to leave two 65 openings *H' II'* between it and the said cam

for the entrance of the roller *u'* on the upper arm of the cam-lever *U*.

The operation of tripping the cam-lever by hand to produce the shifting of the tympan is as follows: The operator moves the hand-lever *W'* in a direction, and the proper distance to throw out the hook 20 of the trip-lever from the end of the cam-lever—that is 70 to say, until it comes in contact with the stop *x'*. The cam *u* cannot, however, then move outward to its operative position until the space *H'* between the cam *H* and the flange or projection *z* arrives opposite the roller *u'* 75 on the cam-lever. The cam-lever *U* will then be permitted to move a little way in the direction to throw the cam *u* outward, but the said lever will be thrown back by the cam *H*. The hand-lever *W'* must still be held against 80 the stop-pin *x'*, and when the space *H'* reaches the roller *u'* the said roller will pass through the said opening *H'* and within the inner circumference of the flange *z*, during the continued rotation of which the said lever is held 85 with the cam *u* in the position for operating upon the levers *n* of the feed-rollers until the several tympans have been shifted, as hereinbefore described, when the cam *H* comes 90 into operation on the said roller *u'* and brings the cam-lever back to the position to be engaged by the hook 20 of the trip-lever *W*, the operation of the shifting being then completed. As soon as the operator sees the cam *u* thrown into its operative position he can 95 release the hand-lever *W'*, which will be thrown back by its spring *Y* after all the 100 tympans have been shifted and the cam-lever has been returned by the cam *H* to the position to be engaged by the hook 20 of the trip-lever.

The hereinbefore-described means of providing for the tympan-shifting mechanism by hand may be used in the same machine with the automatic mechanism herein first described for operating the trip-lever *W*, or it 110 may be used without the said automatic mechanism.

As the roll of paper on the take-up roller *j* increases in circumference the movement imparted to the said roller *j* from the feed-roller *h* for the taking up of the tympan as it is shifted by the said roller *h* must be diminished; otherwise there would be risk of tearing the tympan. It is to obviate this difficulty and to cause the take-up roller to take up the tympan just as fast as is necessary that I employ the friction-gears *k* and *l* between the said rollers *h* and *j* to drive the latter. These friction-gears are so proportioned that they will 120 drive the take-up roller fast enough when the said roller is empty, and as the quantity of paper rolled upon it increases a slip occurs between the friction-gears; but the take-up roller is always driven fast enough to wind 125 the tympan up tight.

The foregoing description of the construction and operation of my invention will, I believe, be sufficient to enable those skilled in

I have hereinbefore described a ratchet-wheel d^2 on each of the tympan-rollers d , and a pawl d^3 for engaging the same. This pawl d^3 requires to be thrown out of gear from its 5 respective ratchet-wheel prior to the operation of shifting the tympan. For the purpose of throwing this pawl out of gear with its ratchet, it is connected with the outer end of its respective lever n by means which I 10 will now describe with reference to Figs. 2 and 3.

11 is a rod connecting the outer end of the lever n with one arm 12 of a rock-shaft 13, which is supported in the ring A^4 and the adjacent cylinder-head, another arm 14 of the said rock-shaft being connected by a rod 15 with the outer end of the pawl-lever d^3 . For the purpose of keeping this pawl in gear at all times, except when the pawl is intended 20 to be thrown out of gear with its ratchet-wheel, there is coiled round its respective rod 11 a spring 16, one end of which has a bearing against a fixed guide 17, secured to the ring A^4 , the other end of which bears against a 25 collar 18 on the said rod. This spring 16, while strong enough to hold the pawl in gear until it is required to be thrown out, is not strong enough to overcome the friction between the bushing p and the screw-threaded sleeve to 30 which the said lever n is attached.

In order to provide for the insertion of the tympan-rollers d and j into the cylinder and their removal therefrom with the roll of paper which serves as the shifting tympans, the 35 bearings d' and j' for the said rolls are not made directly in the cylinder-heads, but in cap-pieces G , which are fitted to openings G' , provided in the cylinder-heads, the said openings being large enough to permit the insertion 40 of the said rollers and the roll of paper through the cylinder-heads. Each opening G' is represented of a size and form to admit the roller d of one tympan and the roller j to the next tympan. The cap-plates G are of 45 skeleton form, having openings in them large enough to admit the arms of the attendants for the purpose of making ready the tympans for printing.

Before describing the operation of shifting 50 the tympan I will mention that the blanket which is represented under the tympan in dotted lines in Fig. 3 may be attached to one end of the rod a , hereinbefore mentioned as one of the guides for the tympan, and at the 55 other end to a rod b , which is supported in the cylinder-heads.

The operation of shifting the tympan is as follows: The shifting tympan having been put on each section of the cylinder, as described, the extremity u^* of the cam-lever N is brought into the inner hook 20 of the trip-lever W , in which position the movable cam u will be out of the way of the rollers m of the levers n , the said levers being then in 60 such position that the screw-threads on their surface hold the clutches t out of gear, keeping the feed-rollers h out of gear from the

spur-gears s . When the levers are in this position, their rollers m' are in such position that they will not strike the stationary cam N in their rotation with the cylinder. The press being then started, the cylinder revolves in the direction of the arrow 23. (Shown in Figs. 2 and 3.) The gear F revolving with the cylinder in gear with the stationary gear D and the loose gear E causes the latter to turn slowly in the opposite direction to the cylinder at the rate of one tooth for each revolution of the cylinder. After a certain number of revolutions have been made the gear E is turned until the stud 9 on its hub comes in contact with the roller 10 on the trip-lever W and moves the said lever so far that its inner or upper hook 20 slips from under the extremity u^* of the cam-lever U and allows the said cam-lever to be forced outward by the spring into the outer or lower hook 21, as shown in Fig. 2. Then, when the portion of a tympan which is exposed on the surface of the cylinder is clear from the web of printed paper, the roller m on its respective lever n comes in contact with the movable cam u on the lever U , and the said lever n is turned in the direction of the arrow 24. (Shown in the lower part of Fig. 2.) This movement of the lever n , operating through the rod 11 and through the connections hereinbefore described between the said rod 11 and the pawl d^3 , liberates the ratchet-wheel d^2 . At the same time the screw-threaded sleeve o , turning with the lever n , to which it is attached, is caused to be screwed inward in its bushing p , and so to push the gear s and the portion of the ratchet-clutch thereto attached into gear with the other portion of the said clutch on the friction-wheel k . The said gear s is always turned while the cylinder revolves, and when the ratchet-clutch comes into gear the feed-roller h turns with the said gear, and the feed-roller i turns with it by the friction of the tympans between them. The take-up roller j is at the same time turned by the friction between the friction-wheels k and l , and thus the tympan is drawn from the roll on the roller d and wound upon the roller j . The feed-rollers h and i turn sufficiently while the lever n of the roller h moves from under the cam u to a position near the cam N to move the tympan in the direction of the circumference of the cylinder a distance about or nearly equal to the distance between two openings e , or about equal to the length of the form in that direction, and thus to present at one operation an entirely fresh and clean portion of the tympan on the exterior of the cylinder. When the feed-roller h approaches the cam N , the roll m' on its lever n strikes the cam N , and the lever n is thus turned in such direction that the screw-threaded bushing o , to which it is attached, is screwed outward in the bushing p and caused to ungear the clutch t , and the tympan then stops shifting. In the meantime the tympan on another section of

the cylinder included between two openings e is shifting. When the several sections of the cylinder have clean tympans and before either feed-roller h of the tympans has reached 5 the movable cam u a second time, the cam H on the cylinder comes in contact with the roll u' on the cam-lever U and lifts the end u^* of the said lever into the upper or inner hook 20 of the trip-lever W , so that the roll 10 m on the lever n of the tympan will pass the said movable cam u without striking. Then the cylinder makes a number of revolutions until the pin 9 again reaches the roller 10 of the trip-lever W , when the cam-lever U is 15 again tripped and the shifting operation is repeated. The number of revolutions thus made before the pin 9 again reaches the roller 10 depends upon the number of teeth in the spur-gears D E . If it be desired to shift not 20 so often, the gears D and E should have a larger number of teeth. The frequency of the shifting may, however, be increased by putting one or more additional pins 9 in the hub E' of the gear E .

25 In some cases it may be desirable to provide for tripping the cam-lever U by hand to produce the shifting of the tympan at a desirable time. In such case, instead of arranging the trip-lever W loosely on the fixed ful-

30 crum 19, as shown and described with reference to Fig. 2, I fasten said lever upon the inner end of a short arbor 19*, as shown in Figs. 8 and 9, which works in a fixed bearing provided in the cylinder-pocket or suitable portion of the adjacent side frame B of the machine, and on the outer end of the said arbor which projects through the outside of the said side frame I affix a small hand-lever W' , by which at the proper time the hooked arm of

35 40 the said lever W may be operated to trip the cam-lever in the same way as when automatically tripped by the action of the stud 9, hereinbefore described. In order to prevent the trip-lever from being moved farther than it is necessary to effect the tripping of the cam-lever, a stop x' is provided for the hand-lever W' . This stop x' is represented as consisting of a pin secured in the outside of the side frame.

45 50 As it is necessary that the tripping should occur at the proper stage of the revolution of the cylinder, as hereinbefore described, some means must be provided by which the tripping at any other time is prevented, and for this purpose I provide upon the outside of the cylinder a flange or annular projection z , (see Fig. 8,) which is concentric with the cylinder, and the external circumference of which is slightly within the radius of the outside of

55 60 the cam H . This flange or projection z is in a position for the roller u' of the cam-lever U to be just outside of it when the end of the said lever is engaged by the hook 20 on the trip-lever. The said flange or projection z is not a complete circle, but terminates on each side of the cam H , so as to leave two openings H' H^2 between it and the said cam

for the entrance of the roller u' on the upper arm of the cam-lever U .

The operation of tripping the cam-lever by hand to produce the shifting of the tympan is as follows: The operator moves the hand-lever W' in a direction, and the proper distance to throw out the hook 20 of the trip-lever from the end of the cam-lever—that is 70 to say, until it comes in contact with the stop x' . The cam u cannot, however, then move outward to its operative position until the space H' between the cam H and the flange or projection z arrives opposite the roller u' 75 on the cam-lever. The cam-lever U will then be permitted to move a little way in the direction to throw the cam u outward, but the said lever will be thrown back by the cam H . The hand-lever W' must still be held against 80 the stop-pin x' , and when the space H^2 reaches the roller u' the said roller will pass through the said opening H^2 and within the inner circumference of the flange z , during the continued rotation of which the said lever is held 85 with the cam u in the position for operating upon the levers n of the feed-rollers until the several tympans have been shifted, as hereinbefore described, when the cam H comes 90 into operation on the said roller u' and brings the cam-lever back to the position to be engaged by the hook 20 of the trip-lever W , the operation of the shifting being then completed. As soon as the operator sees the cam 95 u thrown into its operative position he can 100 release the hand-lever W' , which will be thrown back by its spring Y after all the tympans have been shifted and the cam-lever has been returned by the cam H to the position to be engaged by the hook 20 of the trip-lever.

The hereinbefore-described means of providing for the tympan-shifting mechanism by hand may be used in the same machine with the automatic mechanism herein first described for operating the trip-lever W , or it may be used without the said automatic mechanism.

As the roll of paper on the take-up roller j increases in circumference the movement imparted to the said roller j from the feed-roller h for the taking up of the tympan as it is shifted by the said roller h must be diminished; otherwise there would be risk of tearing the tympan. It is to obviate this difficulty and to cause the take-up roller to take up the tympan just as fast as is necessary that I employ the friction-gears k and l between the said rollers h and j to drive the latter. These friction-gears are so proportioned that they will 115 drive the take-up roller fast enough when the said roller is empty, and as the quantity of paper rolled upon it increases a slip occurs 120 between the friction-gears; but the take-up roller is always driven fast enough to wind 125 the tympan up tight.

The foregoing description of the construction and operation of my invention will, I believe, be sufficient to enable those skilled in
